FOOT MANIPULATING APPARATUS

Daniel W. Davis, Beaumont, Tex.

Application April 5, 1933, Serial No. 664,514

4 Claims. (Cl. 128—69)

This invention relates to the correct adjustment of troublesome maladjusted or defective feet and particularly to apparatus for treating the feet to effect relief from painful strain and maladjustments or defects.

The primary object of the invention is to provide a method of and apparatus for correcting the anatomical maladjustments and/or defects of human feet.

10 The human foot, because of its cantilever construction is ordinarily subjected to multiplied strains which under the most favorable conditions cause tiring of the feet, particularly the arches and attendant structures. In walking or running the weight of the body is repeatedly shifted from the heel to the ball of the foot and during the shifting and while resting on the ball the entire load is transmitted thru and supported by the arch of the foot. Again in standing about 15 for long periods of time when the weight of the body is supported entirely upon the feet there is a resultant downward springing of the arches, as the weight is borne principally upon the heels and toes. These and other normal or abnormal 20 activities cause tiring and weakening of the ligaments of the arches.

It may be seen that excessive or abnormal use or an accident may strain the arches to such extent that a maladjustment will be caused. On 25 the other hand improper footwear may cause an unfavorable condition which will aid in causing a maladjustment, or there may be some natural weakness or defects of a foot which may become aggravated or aid in causing a maladjustment.

30 Numerous painful troubles exist in human feet due largely to the extraordinary foot strains from various causes that the average human experiences in the pursuit of his normal duties. As it is frequently inconvenient or impossible for 35 one to enjoy systematically the careful and frequently expensive attention of experts, these troubles are often neglected. As a result the condition may become so acute as to cause such a degree of disability as to seriously hamper the 40 activities of the victim. Fortunately these troubles may be corrected.

45 The present invention contemplates an apparatus, hereinafter referred to as adjuster, for manipulating affected portions of the arches and attendant structures of the feet to thereby strengthen or develop in those portions normal healthy members which are capable of normal functioning.

50 Among the foremost advantages of the present invention is that an individual may employ it at

any convenient time, such for example as just before retiring at night. Any other convenient time may be chosen but when employing it before retiring at night the natural recuperative powers of the body are given an opportunity to function under most favorable conditions, as the patient will usually thereafter remain prone for several hours.

5 It is pointed out here that the invention may be employed to considerable advantage and great 10 comfort by persons whose feet merely grow tired from the day's activities, as it tends to readjust to normal positions the delicate bone structures of the arches and stimulate and strengthen the supporting ligaments. If so employed it will in 15 fact avoid the consequences of gradually weakening or straining conditions.

The various objects and advantages of the invention may be better understood by referring 20 now to the accompanying drawing, in conjunction with the following description, which illustrate and describe a preferred embodiment of an apparatus, and a method of employing it, according to the present invention.

25 Fig. I is a view of an adjuster taken at an angle from the side and slightly above it.

Fig. II is a view of the handle and lever portion of an adjuster taken from the side and slightly above it.

30 Fig. III is a view in cross section of the resilient presser member of an adjuster taken on the line III—III of Fig. II.

Fig. IV is a view of the boot and adjustable strap member of an adjuster taken at an angle from the front and slightly above it.

35 Fig. V is a view illustrating diagrammatically an adjuster in a position to be manually operated in adjusting the arch of a human foot.

An adjuster complete as illustrated in Fig. I 40 consists of a frame-like combination lever, handle and support 1, a resilient presser member 2 which is rigidly attached to and supported by the member 1, a padded boot member 3 and an adjustable strap member 4.

The member 1, illustrated more completely in 45 Fig. II, is formed preferably from a piece of bright wire bent in such shape as to provide a handle portion 6. The lever portion may be of any convenient length and is bridged at the ends of the pieces projecting from the handle end, by 50 a bar-like member 7 which serves as a rigid support for the presser member 2. A web member 8 is provided at the base of the handle 6 for strengthening and stiffening the member 1 against 55 rotating or twisting about a longitudinal axis.

The resilient presser member 2 illustrated more completely in Fig. III is preferably formed of a wood or the like base, or stock, 10 which is rigidly secured to the bar member 7 by a suitable screw 11. A piece of resilient or sponge rubber or the like 12 is provided to fit the outer end of the stock 10 and a soft rubber cap 13 covers the resilient member 12 and stock 10 in such a manner as to form a well-knit resilient presser member. In an alternate arrangement the two members 12 and 13 may be made integrally, that is of one piece, having the required resilient qualities.

The boot member 3 and adjustable strap member 4 are illustrated more completely in Fig. IV. The boot member 3 is preferably made of flat felt or padding material covered with a suitable strengthening cover fabric. The strap 4 may be of any suitable material, fabric or leather, its ends being secured to the boot member 3, and a buckle 5 being provided for adjusting the size of loop the strap 4 forms. An elastic web member 15 is provided for drawing the lower edges of the boot member 3 together so as to provide a snug fit for a foot. Two strap members 16 and 16 are provided in the form of loops for loosely encircling the projecting members of the member 1 for securing the boot member 3 thereto and providing a fulcrum for the lever 1, the function of which will be fully described presently.

In fitting an adjuster on the foot for applying the manipulative adjustments, as illustrated in Fig. V, the toes may be thrust into the boot 3 and the strap 4 placed around the back of the foot, just above the heel, drawn up to fit snugly and secured by the buckle 5. In the application of the different manipulative adjustments it is usually desirable to manipulate one location to a sufficient degree and then shift to another location. When the location is changed, longitudinally of the foot at least, the position of the boot 3 may be also necessarily changed and accordingly it may be moved from near the tips of the toes to nearer the instep or vice versa according to the preceding positioning. The shifting may be accomplished by thrusting the toes farther into, or thru, the boot 3 or by partially withdrawing them, and correspondingly adjusting the strap 4 to effect a snug fitting of the boot on the fore portion of the foot and the strap around and slightly above the heel. The combination member 1 may then be moved forward or backward, longitudinally the foot, by sliding in the supporting loops 16 and 16, or it may be swung from side to side with or without sliding, so as to place the resilient member 2 upon the exact location on the sole of the foot where the treatment of the arch or other affected part is to be directed. The manipulations of the foot may be then effected by applying and relieving pressure alternately upon the handle 6 by hand, either in a direct line or by a rolling or a lateral movement, the loops 16 and 16 acting as a fulcrum for the lever 1 which exerts pressure upon the sole of the foot thru the presser member 2. Pressure upon the handle 6, to effect the manipulations is properly applied by pressing or springing down firmly and gently on the handle, the projecting lever portions being appropriately resilient, and alternately relieving, or rolling and then relieving, whichever is desired. The lateral or rolling movements produce a kneading effect upon the underside of the arch or other portion of the foot undergoing treatment, while the pressure as taken in a direct line serves to exaggerate the normal arch.

In the application of the manipulation to a foot the strap 4, secured around the heel, serves as an anchorage to prevent the snugly fitting boot 3 from slipping toward the outer ends of the toes. When perpendicular or lateral or angular pressure is applied to the handle portion 6 a corresponding pressure is brought on the top or side or side and top, respectively, of the anterior portion of the foot. A resultant pressure in the opposite direction is also brought on the under side or side of the foot, as the case may be, by the presser member 2 secured to the end of the lever 1, opposite the handle end, which is fulcrumed in the loops 16 and 16. The opposing pressures thus effected on the top of the anterior portion and the underside of the arch portion of the foot serve to depress the anterior portion and spring the arch into an arched position which is exaggerated from the normal. As the anterior portion of the foot is depressed the normally snug fitting strap 4 is drawn tighter around the heel and a corresponding pressure or pull is exerted upon the heel which has a tendency to draw it forward and slightly downward thus aiding in manipulating the arch into the exaggerated position.

The pressure upon the top of the anterior portion of the foot is preferably distributed by the boot 3 over the area it covers while in contrast the pressure upon the under side of the foot is fairly concentrated by the presser member 2 at the exact point desirable. By repeatedly applying and relieving the pressure upon the handle 6, alternating with a rolling movement to effect a kneading of the parts while continuing to apply desirable pressure, and shifting the location of the presser from time to time, a healthful stimulation of the normal circulation and draining of the articular surfaces may be realized.

Following the general mode described above, the method of applying the manipulative adjustments may be directed to all portions of the underside and/or the inside of the foot thus effectively relieving the strained distorted condition. As an individual becomes adept in the use of the apparatus the various benefits to be derived from its use will be more fully realized. A novice, however, may employ the device, following the method herein-set-forth, and from the beginning afford himself a profitable degree of relief and begin the ligament strengthening and correcting process. A study of one's particular pedal troubles and increasing skill in the use of the device will enable one to follow well organized systems for the proper local treatment of an ailing part as contrasted with a general treatment of the entire foot.

It is pointed out that the diameter or size of the contact surface of the presser member 2 and its degree of resiliency is preferably adapted for the different systems of manipulative adjustments. For example a fairly large knob-like, or laterally disposed bar-like, soft presser member may be employed for a general kneading of the entire under portion of the foot to obtain relief from an exceedingly tired or cramped condition. While a fairly small and harder presser member may be employed for concentrating the pressure applied to a confined area, as when manipulatively adjusting and strengthening a toe joint which might have been misplaced at some remote or more nearly previous time. Varying graduations of shapes, sizes and degrees of resiliency of the presser members may be employed for the treatment of disordered tarsal, metatarsal phalanges and so on.

It may be obvious that a number of modifications of the invention, with particular reference to the apparatus may be effected without departing from the spirit and the scope of the invention which depends entirely upon the definitions contained in the appended claims.

I claim:—

1. An apparatus for manipulatively adjusting the feet from beneath comprising a soleless partial cover arrangement for a foot covering the upper portion of the toes and securing around and slightly above the heel and a combined movable lever and knob-like presser member disposed beneath the foot fulcrumed by an attachment to the toe covering portion and adapted for applying local pressure to the sole of a foot.
2. An apparatus for manipulatively adjusting the feet from beneath comprising a soleless partial cover arrangement for a foot covering the upper portion of the toes and securing around and slightly above the heel, an elastic web member for drawing the edges of the toe covering member snugly together around the toes and a combined movable lever and knob-like presser member disposed beneath the foot fulcrumed by an attachment to the toe covering portion and adapted for applying local pressure to the sole of a foot.
3. An apparatus for manipulatively adjusting the feet from beneath while restricting expand-

sible movement of the anterior portion of the foot comprising a boot-like member covering the toes, a strap passing around and slightly above the heel adapted to secure the boot-like member on the toes and a combination movable lever, handle and knob-like presser member depending from and fulcrumed by the boot-like member and extending longitudinally beneath the foot and adapted to apply local pressure to the sole of the foot.

4. An apparatus for manipulatively adjusting the feet from beneath comprising a boot-like member for covering the anterior portion of the foot and restricting laterally expansible movement of the toes and upper joints thereof, a longitudinally adjustable strap for passing around and slightly above the heel of a foot, a combined movable handle and lever member slidably secured to the boot-like member and adapted to extend longitudinally beneath the foot, loop-like members for securing the lever member to the boot-like member which also serve as a fulcrum for the lever member, and a knob-like presser member resilient with relation to its end surface which is rigidly secured to the end of the lever member opposite the handle portion and adapted to apply pressure locally to the soles of feet.
